UNITED STATES PATENT OFFICE

144,293

DESIGN FOR A WATCH BAND OR SIMILAR ARTICLE

John Evans, Union, N. J.

Application October 2, 1945, Serial No. 122,465

Term of patent 7 years

(Cl. D45—4)

To all whom it may concern:

Be it known that I, Robert H. Ischinger, a United States of America and a resident of Union, Essex County, State of New Jersey, have invented a new, original, and ornamental Design for a Watch Band or Similar Article, of which the following is a specification, reference being had to the accompanying drawing, forming a part hereof in which

Figure 1 is a top plan view of a watch band, or similar article, showing my new design;

Fig. 2 is a side elevational view thereof;

Fig. 3 is an end elevational view thereof; and

Fig. 4 is an inverted plan view thereof.

I claim:

The ornamental design for a watch band or similar article, as shown.

JOHN EVANS.
